JOEL M. WHEELER, OF OXFORD, CONNECTICUT.

Letters Patent No. 72,348, dated December 17, 1867.

IMPROVED STEAM-JET FOR CLEANING BOILER-TUBES.

The Schedule referred to in these Letters Patent and making part of the same.

TO ALL WHOM IT MAY CONCERN:

Be it known that I, JOEL M. WHEELER, of Oxford, in the county of New Haven, and State of Connecticut, have invented a new and useful Improvement in Cleaning Boiler-Flues, &c.; and I do hereby declare that the following is a full, clear, and exact description thereof, which will enable others skilled in the art to make and use the same, reference being had to the accompanying drawings, forming part of this specification, in which—

Figure 1 is a longitudinal central section of one form of the instrument for applying my invention, taken through the line $x' x'$, fig. 2.

Figure 2 is a cross-section of the same, taken through the line $x x$, fig. 1.

Figure 3 is a longitudinal section of another form of the same, taken through the line $y' y'$, fig. 4.

Figure 4 is a cross-section of the same, taken through the line $y y$, fig. 3.

Figure 5 is a side view of another form of the same.

Figure 6 is a longitudinal section of the same, taken through the line $v v$, fig. 7.

Figure 7 is a longitudinal section of the same, taken through the line $z z$, fig. 5.

My invention has for its object to furnish an improved means for cleaning the tubes, flues, tube-boxes, &c., of steam-boilers easily, conveniently, and thoroughly, which may be applied without hauling the fires, or while the ship is under way, and which cannot injure the flues or cause them to leak; and it consists in the construction of a device having angular jets for the passage of steam, and in the means by which said jets are rendered available.

This improvement was originally devised for removing the ashes, &c., and cleaning out the spaces between the tubes in boilers, and is equally applicable to vertical or horizontal boilers.

A, B, and C are heads, which are designed to introduce the angular steam-jets into the spaces to be cleaned. The head A, which is designed more particularly to be used in cleaning the spaces between the tubes of vertical boilers, is made in three pieces, $a^1 a^2 a^3$, which are secured to each other by screws passing through the part or piece a^3 , and through lugs, a^4 , cast upon the inner surfaces of the parts a^1 and a^2 , as shown in the drawings. All around the end piece a^3 is formed a narrow space or opening, inclining outward, through which the jet of steam escapes in thin sheets, so as to have a rectangular form in its cross-section, this form of the jet enabling the steam to act upon the forward sides of the tubes, where brushes could not reach, and the tendency being to concentrate the ashes and drive them, through the space through which the head A is being passed, into the back connection, whence they can be readily removed. Through the middle of the end piece a^3 is formed a circular hole, for the passage of a jet of steam to assist in driving the ashes through the space between the tubes into the back connection, the end slits or spaces in the head A also enabling the steam to clean off the upper and lower sheets of the tube-box. Upon the sides of the head A, between the pieces a^1 and a^2 , are slots or spaces, inclining backward, as shown in fig. 7, through which jets of steam pass in such a direction as to clean off the rear sides of the tubes, so that the ashes may be wholly removed from the tube-box, and the tubes cleaned thoroughly upon all sides.

In the case of horizontal boilers, I prefer to make the head round or cylindrical, as shown in figs. 1, 2, 3, and 4.

The head B is made in two pieces, b^1 and b^2 , which are secured together by screws, passing through the end piece b^2 , and through lugs, b^3 , formed upon the inner surface of the part b^1 . The pieces b^1 and b^2 are so formed as to leave a circular slot or space all around between the parts b^1 and b^2 , as shown in figs. 3 and 4, said space or slot inclining outward, as shown in fig. 3, so as to drive the ashes from the inner surface of the flues, and drive them back into the rear connection. To assist the angular jet to do this, a circular hole is formed through the centre of the piece b^2 , for the passage of a central jet, as shown in figs. 3 and 4. In case the boilers are so constructed and arranged that it may be inconvenient or difficult to get at the rear connection, to remove the ashes, a head, C, made as shown in figs. 1 and 2, may be used. The head C is made in two parts, c^1 and c^2 , connected to each other by a screw, passing through the centre of the part c^2 , and screwing into the end of the part c^1 , as shown in fig. 1. The sides of the inner end of the part c^1 are cut away, except enough to support the end into which the connecting-screw enters, so that the steam may escape freely. The piece c^2 is made cup or bell-shaped, as shown in fig. 1, and has a circular slot or space formed between its edge and the side or shoulder of the part c^1 , as shown in fig. 1. This slot inclines backward, as shown in fig. 1, so that the circular jet of

steam may strike the sides of the flue at an angle, as the head C is being passed through said flue, and drive the ashes into the front connection, whence they may be conveniently removed.

The heads A, B, and C, have screw-threads upon the inner surface of their rear ends, so that they may be conveniently attached to a piece of gas or other suitable rigid pipe, which, for convenience, should be longer than the space or flue into which the head is to be passed, the rear end of which pipe should be connected with the steam-space of the boiler by a flexible steam-pipe.

I claim as new, and desire to secure by Letters Patent—

The head A, constructed with inclined slots or openings, substantially as herein shown and described, and for the purpose set forth.

The above specification of my invention signed by me, this 24th day of July, 1867.

J. M. WHEELER.
